GAS DISTRIBUTING AND COLLECTING
CHANNELS FOR REACTION VESSELS

Charles S. Parker, Philadelphia, Pa., and Robert M. Shirk, Wilmington, Del., assignors to Houdry Process Corporation, Philadelphia, Pa., a corporation of Delaware

Application October 28, 1949, Serial No. 124,058

7 Claims. (Cl. 23—288)

1

This invention relates to gas distributing and collecting channels for reaction vessels, and particularly to the type of channel commonly employed in reactors for converting hydrocarbons in the presence of a moving bed of granular solid particles, and in kilns for regenerating or reactivating by combustion the granular solid particles after they have received a deposit of carbonaceous material as a result of their previous contact with hydrocarbon vapors in the conversion zone. The invention is more particularly directed to systems wherein the granular solid particles are passed downwardly in the form of a moving bed through a vessel in which a plurality of inverted channel members are horizontally arranged side-by-side and spaced to provide a grid through which the catalyst passes in traveling downwardly through the vessel. The channel members may be conveniently grouped in a series of vertically spaced grid-forming layers, so that the channels in certain layers may be used to introduce a gaseous reactant to the moving bed of solid particles and the channels in other layers may be used to convey out of the vessel the gaseous reaction products which have become separated from the particles in the zones beneath the channels. A typical system embodying structure to which the present invention is especially applicable has been described by R. H. Newton, G. S. Dunham, and T. P. Simpson in a paper entitled "The T. C. C. Catalytic Cracking Process for Motor Gasoline Production," reported in Transactions of American Institute of Chemical Engineers, volume 41, Number 2, April 25, 1945.

For the purpose of illustrating the invention the channels will hereinafter be referred to and described in connection with a kiln for regenerating the catalyst.

Heretofore, it has been a common practice to support the ends of the channel members on short complementary-shaped channel sections attached to the chamber wall and to the central beam, and adapted for nested engagement with the channel ends, provision being made for limited longitudinal movement of the channels to allow for expansion requirements in view of the high temperatures employed in the kiln. Several disadvantages are inherent in this type of construction, the principal disadvantage being the lack of uniform gas seal between the ends of the channels and the side walls of the beam header or of the vessel, depending upon whether internal or external manifolding is employed, as a result of longitudinal shifting of the channels on the supports. Failure to maintain an adequate seal

2

permits by-passing of the oxygen-containing gas through the space between the end of the channel and the adjacent wall surface directly into the bed above the channel, producing an undesirable concentration of oxygen at such point, and also permits by-passing streams of gaseous products of combustion to carry solid particles into the flue outlets. Various expedients have been employed to maintain the channels in their proper position but these expedients usually included fastening means, such as straps or bolts, which, while they overcame the problem of shifting, introduced a different problem in that the work of assembling and dismantling the units required additional expenditures of time and labor.

In accordance with the present invention the channels are supported at the ends which are in communication with the gas inlet or gas outlet conduits by members having contacting support surfaces inclined to the vertical, so arranged that the end-plate of the channel is constantly urged in the direction of its opposite sealing surface. The opposite ends of the channels are supported on suitable members which are fixed with respect to the chamber wall, sufficient clearance being left between the end of the channel and the supporting means to permit longitudinal movement of the channel, such as may occur when the channel is expanding as a result of increased temperature or when the channel is being installed or removed.

The invention is adapted to be used in either a system in which the channels are continuous for the full width of the kiln and are externally manifolded, or a system in which a beam manifold is provided diametrically across the kiln with lateral conduits on either side communicating with the channel. In either case, the same construction may be provided for the end of the channel communicating with the manifold.

For a more complete understanding of the invention reference may be had to the accompanying drawing forming a part of this application, in which:

Fig. 1 is an elevation view of a typical kiln embodying the channel construction of the present invention, in which a portion of the kiln has been broken away to show in section the details of the channel structure.

Fig. 2 is a fragmentary enlarged view of a single channel with a portion broken away to show the details of construction at the ends.

Fig. 3 is a section view taken along the line 55 3—3 of Fig. 2; and

Fig. 4 is a view showing a preferred channel arrangement for use in a circular kiln, in which the gas manifolds extend diametrically across the kiln.

Referring to the drawing, Fig. 1 shows a typical regenerator or kiln, such as may be used in connection with the catalytic cracking of hydrocarbons, generally indicated by the numeral 11. Granular catalytic material withdrawn from a reaction zone, not shown, and bearing a carbonaceous deposit thereon, is introduced to the kiln through an inlet 12 located centrally in the upper end. Within the kiln 11, the catalyst passes downwardly as a compact moving bed through a series of regeneration stages, several of which are shown through the opening formed by breaking away a portion of the vessel. After a residence time within the kiln sufficient to remove by combustion the carbonaceous deposit, the regenerated catalyst is withdrawn from the bottom of the kiln through outlet 13, after which it may be reintroduced to the aforementioned reaction zone. In the specific embodiment illustrated in Fig. 1 the gas distributing and collecting channels of the present invention are shown in connection with a kiln of rectangular cross-section, but it is to be understood that the invention is not so limited, and that the channels and channel supporting devices hereinafter described in detail may be used in kilns of circular or other desired cross-section.

In passing downwardly through the kiln 11, the moving bed of catalyst passes successively through a series of grids, each comprising a plurality of inverted channels arranged side-by-side in a horizontal plane and laterally spaced to provide narrow spaces or slots through which the catalyst may pass downwardly. The series of horizontal grids formed by the channel members are vertically spaced within the kiln so that the catalyst bed which has been separated into individual streams in passing through a grid may reform into a single compact mass before again being subdivided in passing through the next lower grid. In the embodiment of Fig. 1 three such grids are illustrated, the middle grid, generally indicated by the numeral 14, being a gas distributing grid, and grids 15 and 16 disposed above and below the grid 14, respectively, being gas collecting grids. Oxygen containing gas, such as air, is introduced into the moving catalyst bed through the channels of grid 14, part of the gas passing upwardly toward the vapor collecting grid 15 countercurrent to the downward flow of catalyst, and the remaining portion of the oxygen containing gas passing downwardly toward the lower vapor collecting grid 16 concurrent to the moving catalyst bed. Engagement between the catalyst and the oxygen containing gas entering the kiln, and disengagement between the catalyst and the gaseous products of combustion leaving the kiln, is effected in the free spaces immediately below the channels, the mass of catalyst passing downwardly through spaces 17 between adjacent channels, shown in Fig. 2, forming engaging surfaces extending from the lower edges of the channel where the catalyst leaves the space 17, downwardly to a point where the separate streams of catalyst from adjacent spaces 17 unite in a common bed below the grid.

The details of the channel members forming grids 14, 15 and 16 and the means for supporting them within the kiln are shown enlarged in Figs. 2 and 3. Referring to Fig. 2, a channel

is shown as comprising three separate sections interengaging to form a continuous inverted V-shaped channel. Each channel consists of two identical elongated end sections 18, of sufficient length to extend from a point near the center of the vessel to a point adjacent the side wall, and a short intermediate section 19 adapted at each end to fit under the inner ends of channel sections 18, in an overlapping nested arrangement. The middle sections 19 of a single grid are rigidly attached, as by fillet welds along the lower edges thereof to the upper surface of the conventional center beam 20 which extends diametrically across the kiln at a right angle to the channels, the end of the beam 20 being rigidly connected to the walls of the kiln in any suitable manner. A transverse rod 21 extends across each channel section 18, projecting through the side walls in the lower inner corners thereof, the rod being rigidly held in position by nuts 22 threaded on the outer ends of the rod. The lower corners of the short channel section 19 are undercut so that the ends of section 19 may fit within the channel members 18, just clearing the transverse rod 21. In assembled position, the inner end of sections 18 rest on the outer ends of section 19, with the transverse rod 21 positioned beneath and adjacent the lower edge 22 formed by undercutting the lower corners of section 19. The inner end of channel 18 is thus free to move longitudinally a limited distance in overlapping short channel section 19, contact of rod 22 with the vertical edge 23 formed by undercutting section 19 limiting its movement. The lower inner corners of channel sections 18 are also undercut slightly to permit the undersurfaces 24 to clear the center beam 20 when the channel sections 18 are moved inwardly beyond the edge of the beam, as may occur when the grids are being assembled or dismantled.

The outer end of channel section 18 is closed by an end-plate 25 having a vertically elongated central opening 26 adapted to receive the inner end of a conduit 27 extending through the side wall of the chamber, the conduit 27 being either an inlet or an outlet dependent upon whether the associated channel is in a gas distributing grid or in a gas collecting grid. The outer end of conduit 27 may be connected to a horizontal external manifold 28 which communicates with each of the channel conduits 27 at the end of a grid. Referring to Fig. 1, a riser 29 supplies oxygen-containing gas to manifold 28 associated with the conduits of grid 14, and a riser 31 serves as a flue for manifolds 28 associated with the conduits of grids 15 and 16.

The inner face of end-plate 25 is provided with projections 32 on either side of opening 26 the forward surfaces 33 of which slope downwardly and inwardly toward the surface of the end-plate, giving the appearance of wedges attached to the inner face of the end-plate.

The outer face of end-plate 25 is in contact with the vertical side wall 34 of an insulation retainer 35 of L-shaped cross-section extending horizontally along the side wall of the chamber 11. The conduits 27 pass through the retainer 35 and are embedded in castable refractory insulation material 36. Refractory material 37 of any suitable type lines the wall of the chamber 11 above and below the retainer 35. The short pipe section 27, which extends inwardly through the insulated wall of the kiln 11 passes through the opening 26 in the channel end-plate 25 and terminates at a point a short distance

within the channel. A thrust collar 30 mounted on pipe 27 within the retainer 35 is rigidly secured along its inner circumference to the pipe section 27 and along its outer circumference to the vertical wall 34, as by welding.

The inner end of pipe section 27 is provided with a pair of diametrically opposite lugs 38 secured to the outer surface of the pipe on a horizontal diameter. The surfaces 39 of the lugs facing outwardly toward the wall of the kiln are inclined to the vertical, the inclined surfaces being complementary to the sloping portions 33 of the wedge-like projections 32. Immediately below the sloping surfaces 33 notches 41 are formed in the end-plate 25 at the sides of the opening 26. The notches 41 are slightly larger than the lugs 38, so that when the channel end-plate 25 is slipped over the end of the pipe section 27 the lugs 38 pass through the notches 41. When the end-plate 25 is brought into contact with the vertical wall 34 of the insulation retainer the end of the channel is permitted to fall in place so that the sloping faces 33 of the wedge-like projections 32 contact the complementary sloping portions 39 of the lugs 38. The wedge connection formed by the projections 32 and the lugs 38 force the end-plate 25 against the vertical wall 34 so that there is an effective seal between the two against the by-passing of gas directly to the space above the channel, and against the admission of catalyst into the flue outlets.

Referring to Fig. 4 of the drawing a modified arrangement of the channels is shown which is especially suitable for use in a kiln of circular cross-section, although such arrangement may also be used in a kiln of rectangular cross-section when it is desired to provide internal headers for introducing combustion supporting gases to the channels and for removing gaseous products of combustion therefrom. Fig. 4 shows fragmentary portions of a kiln 42 of circular cross-section in which a central beam 43 supports a header or manifold 44 provided on either side with short pipe sections 45, these pipe sections being similar to but shorter than pipe sections 27. The channel sections 46 of this modification have end-plates 25 at their inner ends which are held in abutting engagement with the outer side surface of the header 44. The outer end of channel section 46 may be supported on a bracket member 47 attached to the wall of the kiln, a sufficient space being provided between the refractory lined wall and the end of the channel to allow for expansion of the channel with increasing temperature. An end-plate 48 closes the outer end of channel 46. The end-plate is set inwardly from the channel end, thus providing a recess 49 to receive catalyst that has become trapped between the end of the channel and the refractory lining of the kiln. Downwardly sloping louvers 50 are set horizontally in the recess 49 to permit catalyst to rise upwardly therein when the expanding channel is forced against the trapped catalyst.

The channel of the present invention is self-locking and may readily be installed or removed. By reason of the wedging device between the end of the channel and the wall of the kiln, the weight of the bed of catalyst above the channel applies additional force to provide an effective seal at the end of the channel.

While the invention has been particularly described in connection with a kiln for regenerating catalyst, it is to be understood that it is

equally well adapted for use in other reaction vessels.

We claim:

1. In a gas-handling grid for a vertical vessel in which gaseous reactants are contacted with a compact moving bed of granular contact material, said vessel having an internal vertical grid-supporting surface in contact with said moving bed, the combination of a relatively short conduit extending from said grid-supporting surface and having a radially projecting lug member at each side of its free end, said lug member having its rearward face inclined downwardly and inwardly toward said grid-supporting surface, an inverted horizontal trough member having an end closure plate provided with an opening to receive said conduit, said opening being vertically elongated to permit limited vertical movement of said trough member with respect to said conduit and being horizontally extended by cut-out portions at the sides adapted to receive said lug members, and wedge-like members projecting from the inner face of said end closure plate immediately above said cut-out portions, the end surfaces of said wedge-like members being sloped complementary to the inclined surfaces of said lug members, the arrangement of said lug and wedge-like members being such that, when said conduit is inserted through the lower portion of said elongated opening to a point where said wedge-like members are rearwardly of said lug members and said trough member is released, the sliding engagement of said complementary inclined surfaces will force said end plate tightly against said vertical grid-supporting surface.

2. Apparatus as defined in claim 1 in which said vertical grid-supporting surface is the side wall of said vessel.

3. Apparatus as defined in claim 2 including means supporting the opposite end of said trough member and adapted to permit free longitudinal movement thereof in response to changes in temperature.

4. Apparatus as defined in claim 1 in which said vertical grid-supporting surface is a side wall of a gas manifold conduit passing transversely through said bed.

5. Apparatus as defined in claim 4 in which the opposite end of said trough member is freely supported on a support member extending inwardly from the wall of said vessel, and including an end closure plate for said opposite end, and a plurality of vertically-spaced horizontal louver-like members sloping downwardly and outwardly from said opposite end closure plate and terminating adjacent to said vessel wall, the space between said vessel wall and said opposite end closure, and having said support member as its lowermost boundary, being adapted to contain a static compact mass of said contact material which is forced by the longitudinal expansion of said trough member upwardly into the spaces between said louver-like members.

6. In a gas-handling grid for a vertical vessel in which gaseous reactants are contacted with a compact moving bed of granular contact material, and including a gas manifold conduit passing transversely through said bed, an inverted horizontal trough member supported at one end in substantially gas-tight connection with the side of said manifold conduit, a relatively short conduit connecting said trough member to said manifold conduit, support means extending inwardly from the wall of said vessel and freely supporting the opposite end of said trough mem-

ber; an end closure plate for said opposite end, and a plurality of vertically-spaced horizontal louver-like members sloping downwardly and outwardly from said opposite end closure plate and terminating adjacent to said vessel wall; the space between said vessel wall and said opposite end closure, and having said support member as its lowermost boundary, being adapted to contain a static compact mass of said contact material which is forced by the longitudinal expansion of said trough member upwardly into the spaces between said louver-like members.

7. In a gas handling grid for a vertical vessel adapted for conducting a reaction of gaseous reactants in the presence of a compact moving bed of granular contact material, an inverted trough member closed at one end by an end plate provided with a vertically-elongated central opening, a conduit extending through a side wall of said vessel and projecting inwardly through said opening, the inner end of said conduit having lug members extending outwardly along a horizontal diameter, and having inclined rearward surfaces, said opening in said end plate being and arranged to permit limited vertical

movement of said end plate with respect to said conduit and having cut-out portions at either side adapted to receive said lug members, the inner face of said end plate being provided with wedge-like projections immediately above said cut-out portions, the outer surfaces of said wedge-like projections having a sloped surface complementary to the inclined surfaces of said lug members and being inclined at an angle to

the vertical such that when said conduit is inserted into said opening to a point where said lugs extend beyond said projections and the end of said trough member is lowered to bring into engagement said complementary inclined surfaces, the force of gravity will cause said end plate to be urged into substantially gas-tight contact with said vertical wall surface.
